Des. 183,938
Patented Nov. 18, 1958

183,938

LINK CHAIN FOR A BRACELET OR THE LIKE

Adolph Katz, Providence, R. I., assignor to Coro, Inc.,
New York, N. Y., a corporation of New York

Application April 8, 1958, Serial No. 50,394

Term of patent 7 years

(Cl. D45—4)

Fig. 1

Fig. 2

Fig. 1 is a plan view of a link chain for a bracelet or the like showing my new design.

Fig. 2 is an edge view thereof.

I claim:

The ornamental design for a link chain for a bracelet or the like, substantially as shown.
